UNITED STATES PATENT OFFICE.

GEORGE ROOKE, OF EMPORIA, KANSAS.

SCREW PROPELLER.

SPECIFICATION forming part of Letters Patent No. 464,898, dated December 8, 1891.

Application filed October 15, 1891. Serial No. 408,768. (No model.)

To all whom it may concern:

Be it known that I, GEORGE ROOKE, of Emporia, in the county of Lyon and State of Kansas, have invented certain new and useful 5 Improvements in Screw Propellers, of which the following is a specification, reference being had to the accompanying drawings.

The object of my invention is to improve the mechanism for propelling the ship from 10 the bow, so that increased speed may be secured beyond what can be obtained by driving a boat from the stern.

My invention relates to boats wherein the bow is formed in two separate parts, one normally above and the other below the water-line. I provide a revolving conical beak (or 15 extension of that part of the bow which is under water) having blades that tend to draw the ship through the water and having pecu- 20 liar spiral projections back of the blades that diminish the pressure of water upon the bow, and thus tend to increase the speed of the ship.

My present invention relates particularly 25 to such devices combined with a hollow cylindrical shell which may be applied around the propeller-blades, so as to be either fixed or to rotate with them and to inclose them, substantially as illustrated in the drawings, in 30 which—

Figure 1 is a side elevation of so much of the forward part of the hull of a boat as is necessary to illustrate my invention, the shell being shown in section. Fig. 2 is a section on 35 the line 2 2 of Fig. 1. Fig. 3 is a section on the line 3 3 of Fig. 1. Fig. 4 is a cross-section of the shell, illustrating it as fixed to the boat.

Referring to the letters on the drawings, A 40 indicates the hull of a boat, which is provided at its bow with a separate deck part A' and between the keel and the water-line with a conically-tapered part B, which may be built into the boat or may be provided in one already built by removing a part of the hull and 45 rebuilding that portion of it. Any kind of boat, whether old or new, may thus be adapted to use my improvements.

C indicates a conical beak whose base is of 50 the same diameter as the part B, where the beak joins it, and whose sides form a continu-

ation of the taper of that part. It is mounted by means of the shaft D on suitable bearings E in the interior of the vessel and in the forward part of the keel F, respectively, and is 55 adapted to be rapidly revolved by any suitable mechanism. (Not shown in the drawings.) Upon the forward end of the beak are provided blades G, so arranged thereon as to tend to draw the boat through the water when 60 the beak is revolved. Near the largest part of the beak and behind the blades on the beak are provided spirals H, that preferably consist of ribs arranged obliquely and parallel to each other. They should be constructed 65 substantially as shown, so as to throw the water away from the bow of the boat, thereby diminishing the resistance against its onward movement and at the same time so as to cause in themselves the minimum resistance to ro- 70 tation and to forward motion. The form illustrated in the drawings I regard as preferable for the spirals; but it may be varied. In this form, as shown in the section, Fig. 2, the beak being rotated in the direction of the arrow, 75 the incline K will tend to throw the water away from the submerged part B of the bow and, as it were, open a cavity for the passage of the bow. The front ends of the spiral ribs are tapered at L, so as to wedge their way 80 into the water as the boat advances and also tend, like the inclined sides K, to throw the water away from the submerged part of the bow.

The devices thus far described have been 85 embodied by me in another application for patent; and in the present case I combine with the parts described a hollow cylindrical casing M, inclosing the propeller-blades, the object of which is to guard and protect them 90 while it admits water freely. The opening into the cylinder from the small end of the beak is greater than that at the opposite end, so that ample water is received as the boat advances for the action of the blades of the 95 screw, and by confining the water around the rear of the blades the shell aids the action of the propeller upon the water and tends to increase its pulling force upon the ship, and also forms a shield. This shell may be either 100 fixed or made to revolve with the screw in practice with the same effect. It can be made

of steel or other strong metal and quite thin, so that its resistance to the advance of the ship is but slight, and it more than compensates for its weight and resistance by the service it 5 performs in connection with the propeller-blades. In the drawings it is shown as adapted to rotate with the screw-propeller.

What I claim is—

In a boat, the combination of a revoluble 10 conical beak C, provided with propeller-blades at its forward end and spirals H in rear there-

of, each spiral having the incline K upon one side and the front incline L and means for rotating the beak, and a hollow cylindrical shell M, surrounding the propeller-blades, substantially as set forth.

In testimony of all which I have hereunto subscribed my name.

GEORGE ROOKE.
